ELECTROMECHANICAL SOUND RECORDING
AND REPRODUCING MACHINE

Jacob H. Rebold, Brooklyn, N. Y.

Application February 25, 1941, Serial No. 380,462.

18 Claims. (Cl. 179—100.4)

This invention relates to electro-mechanical sound recording and reproducing machines, and more particularly to such machines as are adapted, through the use of a single combined recording-reproducing unit, to either reproduce sound from a disc record, or to record sound upon a suitably prepared blank disc. This dual functionality requires that means be provided for properly conditioning the system for the particular function it is to perform.

In reproducing, the stylus carried by the recording-reproducing unit must be free to track with the sound groove in the record, and for this purpose usually requires a rounded point resting on the bottom only of the record groove. The axis of the stylus should form an angle of approximately 70 degrees with the plane of the oncoming record surface. The direct electrical output of the stylus-carrying unit being small, it is necessary to connect it to the input of an amplifier, the amplified output of which is applied to a loud-speaker or other means of converting the electrical impulses into sound.

In changing the system over to recording, a number of changes are required for satisfactory operation. The stylus must now present a sharp cutting edge to the oncoming record, and the axis of the stylus be close to vertical to the face of the record. The stylus-carrying unit must be connected to the output terminals of the amplifier, while the input of the amplifier must now be connected to the microphone, radio receiver, or other source of the electric impulses representative of the sound to be recorded. In addition, the stylus-carrying unit must be mechanically coupled to some means for guiding the stylus radially across the rotating record blank, so that the stylus cuts a continuous spiral groove therein.

The primary object of the present invention is to provide improved means for automatically accomplishing the required changes incidental to one function or the other, with a minimum of attention on the part of the operator.

Another object of my invention is to provide a phonograph turntable, circuit switch, and electric tone-arm assembly with at least three distinct areas of operation for the tone-arm including a neutral or "off" area; a reproducing area; and a recording area; and in which the conditioning of the mechanism corresponds to and is dependent solely upon the particular area into which the tone-arm is brought by the operator.

A further object of this invention is to provide

means by which the change of stylus point and change of stylus angle is made automatically dependent upon the position of the tone-arm.

Another object of my invention is to provide improved means by which the required switching of electrical connections between the various components of the recording-reproducing mechanism is made automatically dependent upon the position of the tone-arm.

10 Another object of this invention is to provide improved means by which the tone-arm is automatically coupled with a stylus-feed mechanism when brought into the recording area, and automatically decoupled from the feed mechanism when out of the recording area.

Another object of my invention is to provide a dual function stylus having one side suitably prepared for recording upon a record blank and an opposite side suitably prepared for playing back from a finished record, and means by which that side of the stylus appropriate to the desired function is automatically presented to the oncoming record surface.

Still other objects and advantages of this invention will be apparent from the specification and the annexed drawings, in which:

Fig. 1 is a plan view of a recording-reproducing arm and record turntable arranged according to one form of my invention, the arm being shown in solid lines in its "off" position clear of the turntable, and in dotted lines in the position it would assume at the start of the recording function, assuming the recording is to be from "outside-in" of the record. The broken lines radiating from the vertical pivot of the arm indicate the limits of the recording, neutral, playback, and off areas that can be covered by the long axis of the arm, and are indicated as R, N, P, and O respectively.

40 Fig. 2 is a vertical sectional view taken upon line 2—2 of Fig. 1, showing the details of the arm when it is in its off position, the dotted lines indicating how the recording-reproducing unit may be lowered onto the record when the arm is brought into the P or playback area, the stylus assuming the proper playback angle.

Fig. 3 is a vertical sectional view similar to Fig. 2, but taken with the arm in the position shown by dotted lines in Fig. 1, and shows the 50 details of the arm when it is in the R or recording area, the stylus now being shown in correct recording position.

Fig. 4 is a horizontal sectional view taken upon line 4—4 of Fig. 2, and shows the relative positions of the switch plate, switch-actuating fin-

gers, arm rear-bearing, arm post, and stylus feed bar, when the arm is in its "off" position.

Fig. 5 is similar to Fig. 4, but shows the position of the various parts when the arm is in the playback position.

Fig. 6 is similar to Fig. 4, but shows the position of the various parts when the arm is about to leave the playback area and enter the neutral area.

Fig. 7 is similar to Fig. 4, but shows the position of the various parts when the arm is at the start of the recording position, corresponding to the position indicated in Fig. 3.

Fig. 8 is a vertical sectional view taken upon line 8-8 of Fig. 2, showing the arm in its off position.

Fig. 9 is a vertical sectional view taken upon line 9-9 of Fig. 3, and shows the front view of the arm in the recording position.

Fig. 10 is a schematic circuit diagram of the electrical connections between the various components.

Figs. 11 and 12 are enlarged views of the stylus in the playback and recording positions, respectively.

Figs. 13, 14, and 15 are enlarged views of the tip, front, and rear, respectively, of a suitable dual-function stylus.

Fig. 16 is a partial vertical sectional view of a modified form of arm and feed bar coupling.

Similar numerals refer to similar parts throughout the description and the different views of the drawings.

The baseboard 1 is a general representation of a frame, upon which is mounted the bearing 2, in which turns the shaft 3, to which is attached the turntable 4, carrying the record 5, upon which the recording is to be made, or from which the sound is to be reproduced. The turntable is driven at suitable speed by any of the methods well-known to the art, such as gear drive to the shaft, friction roller drive to the turntable rim, belt drive, etc.

Fastened to the baseboard 1 at a point outside the turntable 4 is a post 6, having a shoulder 7 abutting the top of baseboard 1, and a threaded lower portion 8 cooperating with a lock nut 9 to lock post 6 in a position substantially perpendicular to the baseboard 1. Extending upward from the lower end of post 6 is an axial bore 10, and communicating therewith is a transverse opening 11, the combination of the two forming a passageway through which can be passed the leads from the recording-reproducing unit 12. At its upper end, the post 6 has a curved shoulder 13, and a short cylindrical projection 14 of reduced diameter rising therefrom, with a blind tapped hole centered therein adapted to receive the arm-retaining screw 15. Near its upper end post 6 has a transverse cutaway portion 16 allowing free entry of the tip of rear-bearing screw 17 when arm 18 is swung into recording position, as described more fully below.

Arm 18 is formed with an elongated upper portion having a transverse cross-section of substantially an inverted U shape and near its front end carries the recording-reproducing unit 12, which is normally free to pivot in a vertical plane about the pivots 19 and 20, but is restrained from appreciable transverse movement with respect to the arm 18 by the spacing washers 21 and 22. Near its front end, unit 12 carries the stylus-chuck 23, into which is threaded the stylus clamp-screw 24, which firmly clamps the stylus 25 in substantially a perpendicular position to

the long axis of recording-reproducing unit 12. Inside the front end of arm 18 is fastened the spring clip 26, whose function is to grip the shank of clamp-screw 24 when unit 12 is manually raised to its upper limit of travel, forming a releasable catch holding the stylus in an inactive elevated position when so desired.

The positions of pivots 19 and 20 are so chosen with respect to the center of gravity of recording-reproducing unit 12 that proper weight is placed upon stylus 25 for recording purposes. In the present state of the recording art, using a record blank with a workable coating of cellulose nitrate or similar material from which a thread is to be cut by a sharp-edged stylus, the weight required upon the stylus is in the neighborhood of two to three ounces. The weight of the recording-reproducing unit 12, being usually much greater than the required stylus weight, is arranged about the pivots 19 and 20 so that the greater portion is on the stylus side, and the difference between the two weight components is equivalent to the required stylus pressure. Substantially the same weight is applied to the stylus during the playback operation, two to three ounces having been found to be the optimum pressure for best groove tracking with a rounded-point stylus.

The recording-reproducing unit 12 may be of any of the reversible function types of electro-mechanical transducers capable of either converting electrical undulations into corresponding mechanical vibrations of the stylus, or of converting mechanical vibrations imparted to the stylus into corresponding electrical oscillations. Such convertible units are well-known to the art in both the piezo-electric and electro-magnetic types, and since the constructional details of the recording-reproducing unit are not included in my invention, such details are not shown.

The arm 18 is provided near its rear end with a hollow, downwardly extending elbow 27, having at its lower end a flat bearing portion 28 pierced by a hole 29 of such size as to form an easy slide fit over post 6. Both sides of hole 29 are beveled or chamfered to allow a limited movement of the arm 18 in a vertical plane without binding upon post 6. On its upper side arm 18 has an upwardly cupped portion 30 in substantially vertical alignment with hole 29 and adapted to rest upon the curved shoulder 13. A longitudinal slot 31 is cut in cupped portion 30 of such dimensions as to form a slide fit about cylindrical projection 14 of post 6. The head of arm-retaining screw 15 is wider than slot 31, so that when the arm 18 is placed in position to pivot about post 6, screw 15 will prevent axial movement of the arm along the post.

Elbow 27 carries on its lower front side the downwardly extending legs 32 and 33, and the switch-tripping fingers 34 and 35 extending radially from post 6 as a center. Referring to Figs. 8 and 9, it is seen that leg 32 is longer than leg 33. Leg 32 is made long enough so that it may always contact feed-bar 36 when arm 18 is swung into alignment with the feed-bar, even when the arm is raised vertically to the limit of its travel. Leg 33 is made short enough so that when arm 18 is raised vertically to its playback position, or higher, leg 33 will clear feed-bar 36 vertically, but will contact the feed-bar when the arm is lowered to its recording position. The distance between legs 32 and 33 is made equal to the width of feed-bar 36, so that a close-fitting, re-

leasable coupling is formed when arm 18 is in recording position.

Switch-tripping fingers 34 and 35 are arranged to cooperate intermittently with slots 37 and 38 in switch-plate 39 as arm 18 is swung horizontally into its various operating positions, and are formed with vertically curved leading edges having a vertical width sufficient so that lifting of arm 18 within its normal limits will not change their meshing relation with the slots in switch-plate 39. Fingers 34 and 35 are mutually spaced in a horizontal plane so that the angle formed by the meeting of their respective center lines at the vertical axis of post 6 is substantially equal to the sum of the angles O and P, representing the off and playback areas respectively in Fig. 1.

The front wall of elbow 27 is pierced by an opening 40, through which may be passed leads 41 and 42 from unit 12. The rear wall of elbow 27 near its upper end carries the rear bearing screw 17, its axis parallel with the long axis of arm 18. The tip of screw 17 is tapered to a rounded point which can cooperate with the smooth peripheral surface of post 6 to form a low-friction bearing for horizontal rotation of arm 18 when it is not in the recording position. When the tip of screw 17 leaves the outer surface of post 6 and enters the transverse cutaway portion 16 therein, as it does when arm 18 is swung into recording position, the arm is automatically lowered by the force of gravity until the rear of slot 31 contacts the post projection 14, which then becomes the arm rear bearing.

Feed-bar 36 is an elongated member pivoted at one end about post 6 for limited horizontal oscillation between the limits of the recording area R. This pivoted end rests upon shoulder 7 of post 6, and is so positioned with respect to the lower bearing portion 28 of elbow 27 that when the arm 18 is in the recording position the lower side of portion 28 will contact the upper side of feed-bar 36, while legs 32 and 33 contact the opposite edges. Feed-bar 36 is sloped downwardly from its pivoted end to correspond with the slope of arm 18 when it is in its recording position, assuring a firm connection between the two when in this position, yet allowing the arm to float freely upon its pivot, free of any interference from the feed-bar when the arm is raised to its playback position.

At its opposite end, feed-bar 36 is linked with a feed mechanism capable of moving the feed-bar slowly about its pivot and thus feed stylus 25 radially across record 5 during the recording operation. A suitable stylus feed mechanism is shown in my U. S. Patent No. 2,262,299, issued Nov. 11, 1941, but other mechanisms known to the art may be used. In Fig. 2 is indicated a type of feed mechanism which is positioned between the turntable 4 and the baseboard 1, and includes the feed head 43 containing the feed mechanism driven by shaft 3 and operating to move rod 44 in a plane parallel with turntable 4. At one end rod 44 is provided with a stop 45 preventing further movement of arm 18 when it is swung to the outer limit of the recording area, and at its opposite end carries the coupling yoke 46 coupling it with feed-bar 36. When feed-bar 36 reaches a position corresponding to the inner limit of the recording area, an automatic stop device carried by rod 44 acts to automatically release it from feeding control of feed head 43, thus allowing the turntable 4 to be used for playback purposes without moving feed-bar 36 as long as it remains in this position.

Switch 47 may be of the rotary three-position type, commonly known as three-pole, triple-throw. It may be mounted with its contact portion beneath baseboard 1 by means of nut 48 cooperating with the threaded mounting bushing 49, which extends through and above baseboard 1, as does also the switch control-shaft 50. Control-shaft 50 carries at its upper end the bushing 51, to which is fastened the switch-plate 39, which latter is provided with the radial slots 37 and 38. Slots 37 and 38 are angularly spaced, with respect to the axis of control-shaft 50, by an amount equivalent to the angular displacement required of control-shaft 50 to throw switch 47 from a given position to its next adjacent position, which angular displacement is usually thirty degrees.

The vertical axis of switch control-shaft 50 is so located with respect to the vertical axis of post 6 that when arm 18 is in its "off" position as indicated in Figs. 1 and 4, finger 35 meshes with slot 38 in switch-plate 39. The horizontal distance between the two vertical axes is so chosen that rotation of arm 18 in a counter-clockwise direction results in a clockwise rotation of switch-plate 39, and with it switch control-shaft 50, through just the angle required to throw switch 47 to its next adjoining position, after which further rotation of arm 18 swings finger 35 out of meshing relation with slot 38, leaving the arm free to move within the playback area P without affecting the switch.

The electrical contact portion of switch 47 may consist of the fixed insulating plate 52, around the periphery of which are fastened the equally spaced and radially extending fixed circuit contacts 53, 54, 55, 56, 57, 58, 59, 60, 61, and 62. Journaled to switch control-shaft 50, and positioned in parallel spaced relation with plate 52, is the rotatable insulating plate 63, which carries the movable shorting contacts 64, 65, and 66, spaced ninety degrees apart and adapted to short-circuit adjacent pairs of the fixed circuit contacts.

Referring to Fig. 10, the audio-frequency amplifier 67 may be of the well-known vacuum-tube type, having input terminals 68 and 69, and output terminals 70 and 71. The loudspeaker 72 may be of any well-known type suitable for the purpose intended, its electrical input terminals being represented as 73 and 74. Terminals 75 and 76 represent a source of audio-frequency current representative of sound to be recorded or amplified, such as a microphone, radio receiver, etc. Low-potential terminals 42, 68, 70, 73, and 76 of unit 12, input and output of amplifier 67, loud-speaker 72, and the external source of audio-frequency currents, respectively, are all represented as being at ground potential for audio-frequency currents. High potential terminal 41 of unit 12 is electrically connected with switch terminal 54. High-potential terminal 74 of loud-speaker 72 is electrically connected with switch terminal 61. High-potential input terminal 69 of amplifier 67 is connected with both of switch terminals 55 and 57. High-potential output terminal 71 of amplifier 67 is electrically connected with both of switch terminals 63 and 62. High-potential audio-frequency input terminal 75 is electrically connected with switch terminal 56. Finally, switch terminals 53 and 59 are electrically connected together, while no connection is made to switch terminal 58. Shorting contacts 64, 65 and 66 are indicated in the intermediate or

playback position, each being capable of moving one space in either direction to assume the recording and "off" positions. The heavy radial lines connecting shorting contacts 64, 65, and 66 with shaft 50 represent the insulated mechanical connections between these elements, and not an electrical connection.

Additional switching functions may be accomplished by adding additional stationary circuit terminals and movable shorting contacts to switch 47, in a manner well-known to the art, all under the automatic control of arm 18.

Referring to Figs. 11, 12, 13, 14 and 15, dual-function stylus 25 may be formed with an elongated cylindrical body having at one end a V-shaped flat cutting face 77 ground substantially parallel to the stylus axis, the tip of the V being slightly rounded and the included face angle being made from eighty to ninety degrees, to conform with standard recording practice. Converging rearwardly from each edge of cutting face 77 are the flat clearance faces 78 and 79, the merging of the three faces forming the sharp cutting tip 80, and giving this tip a triangular cross-section.

Intersecting the clearance faces 78 and 79, respectively, are the downwardly and inwardly converging rounded side faces 81 and 82, forming with the periphery of the cylindrical stylus body a V-shaped rounded tracking face 83, the included face angle of which may lie between twenty and sixty degrees, but in any case is smaller than the included face angle of cutting face 77. Tracking tip 84 is rounded on all sides so as to result in minimum wear of the record groove during the playback operation, and is formed of such dimensions as to properly track the groove.

At the end opposite the tracking tip 84, and on the same side of stylus 25, is formed the flat portion 85, adapted to cooperate with the tip of stylus clamp-screw 24 to firmly position stylus 25 in stylus-chuck 23, and assuring proper facing of the stylus with respect to the record. The axial length of stylus 25 from the tracking tip 84 to the top end of the stylus is made slightly less than the axial length from the cutting tip 80 to the top end, so that when the stylus is in its recording position, as indicated in Fig. 12, with the axis of stylus 25 close to vertical to record surface 5, tracking tip 84 will safely clear the record surface while cutting tip 80 is cutting into the record 5.

The operation of my invention may best be understood by first assuming that arm 18 is in its "off" position clear of turntable 4, as indicated in Figs. 1, 2, 4, and 8. Unit 12 is supported in its raised inoperative position by the gripping action of spring clip 26 upon clamp-screw 24. Arm 18 slopes upwardly from its pivot post 6, the weight of the arm being carried by the rounded shoulder 13, the tip of screw 17, and the front side of chamfered hole 29. Feed-bar 36 is in its inner rest position, feed mechanism 43 being held out of feeding relation therewith. Trip-finger 35 is in meshing relation with slot 38 in switch-plate 39, and switch 47 is one position clockwise of the position indicated by the heavy lines of Fig. 10. Movable contacts 64 and 66 short-circuit terminals 55, 56, and 61, 62, respectively. Thus, audio frequency input terminals 75-76 are connected to input terminals 68-69 of amplifier 67, and output terminals 70-71 are connected to terminals 73-74 of loud-speaker 72; while unit 12 is open-circuited. Sound currents applied to terminals 75-76 would

then be reproduced in amplified relation by loud-speaker 72.

To reproduce or playback a record, arm 18 is swung counter-clockwise until stylus 25 is over the starting groove in record 5 within playback area P. The arm has then assumed the position indicated in Fig. 5, trip-finger 35 having been swung out of meshing relation with slot 38 after shifting switch 47 one position to that indicated by the heavy lines in Fig. 10. Movable contacts 64, 65, and 66 now short-circuit terminals 54-55, 57-58, and 60-61, respectively, thus connecting unit 12 to the input terminals of amplifier 67, while loud-speaker 72 is connected to the output terminals of amplifier 67, and audio-frequency input terminals 75-76 are disconnected from operative relation with the amplifier. Mechanical vibrations of stylus 25 by cooperation with the record groove would thus result in a corresponding amplified sound reproduction by loud-speaker 72.

Arm 18 having been swung to playback starting position over record 5, unit 12 is manually released from control of clip 26 and lowered until tip 84 of stylus 25 contacts the record groove, the stylus then assuming the position indicated in Fig. 11, while unit 12 assumes the position indicated by the dotted lines in Fig. 2. By axially adjusting rear bearing screw 17, the vertical slope of arm 18, and in turn the vertical angle of stylus 25 in playback position, may be changed to conform with special conditions as required. When turntable 4 begins rotating in a clockwise direction, arm 18 is free to move horizontally within the playback area P solely under the control of stylus 25 cooperating with the record groove, without interference from switch-plate 39 or feed-bar 36, the latter remaining in its inner rest position during the playback operation.

When the reproducing or playback operation has been completed, arm 18 may then be swung clockwise and returned to its "off" position clear of the turntable. In so doing, trip-finger 35 again meshes with slot 38 from the opposite direction, restoring switch 47 to its first-described condition.

When it is desired to perform a recording operation, arm 18, assuming it is in "off" position, is again swung horizontally in a counter-clockwise direction, passing through areas O, P, N, and R, until stylus 25 assumes a position over the record blank 5 near the outer limit of recording area R. In so doing, arm 18 acts as previously described until it reaches the position indicated in Fig. 6, corresponding to the junction of the playback and neutral areas, P and N, respectively. At this point trip-finger 34 is about to mesh with slot 37 in switch-plate 39, while the tip of rear bearing screw 17, which up to this point had been bearing against the periphery of post 6 and supporting arm 18 in an elevated position, is now about to enter transverse cutaway portion 16 of post 6.

As the swing of arm 18 continues across neutral area N and past the turntable spindle 3, the longer leg 32 of elbow 27 contacts the inner edge of feed-bar 36 as vertical alignment with the long axis of the latter is reached by the long axis of arm 18, so that during the remainder of the arm swing to the start of its recording position, feed-bar 36 is carried along with it. The tip of screw 17 is now opposite the cutaway portion 16, of post 6, and no longer acts to support arm 18 in its elevated position.

Meanwhile, trip-finger 34 has left meshing re-

lation with slot 37 in switch-plate 39, after having moved switch 47 to its remaining position, one step counter-clockwise of the position indicated by the heavy lines in Fig. 10. Movable contacts 64, 65, and 66 now short-circuit terminal pairs 53-54, 55-57, and 59-60, respectively, thus connecting sound current input terminals 75-76 to input terminals 69-69 of amplifier 67, while terminals 41-42 of unit 12 are connected to output terminals 70-71 of amplifier 67, speaker 72 being disconnected therefrom. Audio-frequency currents from a microphone, radio receiver, or other source, applied across terminals 75-76, would thus result in amplified mechanical vibrations of stylus 25, carried by recording-reproducing unit 12.

When arm 18 has been completely swung around to the start of its recording position, it has assumed the position indicated in Figs. 3, 7, and 9, and in dotted lines in Fig. 1, the feed-bar 36 being in aligned position below it. The weight of arm 18 has caused it to assume a downward slope from its pivoted end, the lower bearing portion 26 of elbow 27 now resting upon the upper surface of feed-bar 36, the opposite edges of which are snugly embraced by both the longer leg 32 and the shorter leg 33. The rear side of slot 31 now contacts post extension 14, forming the upper arm bearing about post 6.

The horizontal pivots 19 and 20 of unit 12 have now been brought much closer to the surface of record 5, and when unit 12 is released from spring clip 26 and stylus 25 lowered onto the record 5, cutting tip 80 is first to contact the record surface, tracking tip 84 being held clear thereof, as indicated in Fig. 12. The direction of record rotation with respect to the stylus would now be opposite to that in the playback position, since the stylus is now on the opposite side of the record spindle.

Feed-bar 36, having been brought away from its inner rest position, is now under the control of feed mechanism 43, and when turntable 4 starts rotating, moves slowly inward, carrying arm 18 and stylus 25 with it. In this way, cutting tip 80 engraves a spiral or like groove in the surface of record 5, the walls of which are modulated according to the sound being recorded, in a manner well-known to the art.

After the recording operation is completed, stylus clamp screw 24 is manually raised until gripped by spring clip 26, arm 18 lifted until short leg 33 clears feed-bar 36, and the arm swung clockwise to either the playback or "off" positions. In so doing, the previously described conditions of switch position, arm bearing, and arm slope are automatically restored according to the horizontal position of arm 18.

Feed-bar 36, having been left in some intermediate position in the recording area R upon completion of the recording operation, would continue to feed inwardly upon resumption of turntable rotation subsequently for a playback operation, until it reached its inner rest position, where it would automatically leave the control of feed mechanism 43. However, if the subsequent operation is again a recording operation, arm 18 through the long leg 32 will pick up feed-bar 36 no matter where the latter is left in the recording area R, and carry it outwardly to the recording starting point.

To facilitate inspection or changing of stylus 25 when required, arm 18 may be raised higher than the position indicated in Fig. 2, to a point where the front end of slot 31 strikes the front

side of cylindrical projection 14 atop post 6. This may be done by the operator regardless of where the arm may happen to be, and will allow easy access to the stylus.

From the foregoing description it will be seen that a system has been shown and described which provides for the stylus, recording-reproducing unit, and supporting arm, a main operating area on either side of the record center assigned to a predetermined function of recording or reproducing sound. The simple act on the part of the operator of bringing the stylus to its pre-assigned position on the record for a desired function automatically conditions the system to properly perform that function, without requiring the manipulation of auxiliary change-over levers or other controls, as required with previous systems. The need for close attention and the possibilities of error on the part of the operator are reduced to a minimum, permitting the system to be successfully operated by persons with little experience.

While I have thus far described and shown one form of my invention, I do not wish to be restricted to this exact form, as many changes are possible within the scope of my invention without departing from the range of the appended claims. Several such variations are indicated in Fig. 16. Here the previously described over-baseboard stylus-feed mechanism has been replaced by the feed-screw 86, driven by a gear connection with the turntable shaft, and rotatably mounted with its axis parallel with and below baseboard 1. Feed-bar 36' now has its pivot portion above baseboard 1, but passes downwardly through opening 87 and continues in a plane parallel to and below the baseboard, its opposite end carrying the friction pad 88 adapted to cooperate with the feed-screw 86. At its pivoted end, feed-bar 36' carries bushing 89 containing the radial opening 90.

Arm 18 now has its upper wall pierced by a chamfered hole cooperating with projection 14 atop post 6 to form an upper arm bearing allowing free rotation of the arm in a horizontal plane and limited arm movement in a vertical plane. To allow such limited vertical arm movement, elbow 27' extending downwardly from the pivot end of arm 18 has its lower wall 26' pierced by slot 31' forming a slide fit about the periphery of bushing 89. Threaded through the lower portion of the front wall of elbow 27' is the lower bearing screw 17', its rounded point cooperating with the periphery of bushing 89 when the arm 18 is in playback position and with opening 90 in the recording position. The completely raised position of the arm is indicated by the dotted lines in Fig. 16.

The remainder of the system and the mode of operation may be substantially the same as previously described.

I claim:

1. In a disc sound recording and reproducing machine, a rotatable record turntable, a disc record carried by said turntable and rotatable therewith, a recording-reproducing unit, a support carrying said unit and movable, in a plane substantially parallel to that of said record, to a reproducing position located to one side of a diametric line passing through the center of rotation of said record and lying in the plane of its face, and to a recording position located on the opposite side of said diametric line, whereby the direction of rotation of said record, with respect to said unit,

is opposite in said recording position to that in said reproducing position, a feed mechanism, and means operatively connecting said support with said feed mechanism when said support is in said recording position only.

2. In a disc sound recording and reproducing machine, a rotatable record turntable, a disc record carried by said turntable and rotatable therewith, a recording-reproducing unit, an arm pivot, an arm carrying said unit and manually rotatable about said pivot, in a plane substantially parallel to that of said record, to a reproducing position located to one side of a line passing through the axes of rotation of both said record and said arm, and to a recording position located on the opposite side of said line with respect to said reproducing position, whereby the direction of rotation of said record, with respect to said unit, is opposite in said recording position to that in said reproducing position, a feed mechanism, and means operatively connecting said feed mechanism with said arm when said arm is in said recording position only.

3. In a disc sound recording and reproducing machine, a rotatable record turntable, a disc record carried by said turntable and rotatable therewith, an electro-mechanical recording-reproducing unit, an arm pivot located at a point outside of the perimeter of said record, an arm carrying said unit and manually rotatable about said pivot, in a plane substantially parallel to that of said record, to a recording position located to one side of a line passing through the axes of rotation of both said arm and said record, and to a reproducing position located on the opposite side of said line with respect to said recording position, a recording circuit, a reproducing circuit, a circuit switch controlling the electrical connection of said unit with said recording circuit and said reproducing circuit, and means, controlled solely by the angular position of said arm about said pivot, to automatically condition said switch to connect said unit with said recording circuit when said arm is in said recording position, and to connect said unit with said reproducing circuit when said arm is in said reproducing position.

4. In a disc sound recording and reproducing machine, a rotatable record turntable, a disc record carried by said turntable and rotatable therewith, an electro-mechanical recording-reproducing unit, an arm pivot located outside of the periphery of said record, an arm carrying said unit and manually rotatable about said pivot, in a plane substantially parallel to the plane of said record, to a recording position located on one side of a line passing through both the axis of rotation of said record and that of said arm, and to a reproducing position located on the opposite side of said line with respect to said recording position, a feed mechanism, a recording circuit, a reproducing circuit, a circuit switch controlling the electrical connections of said unit with said recording and reproducing circuits, means operatively connecting said arm with said feed mechanism when said arm is in said recording position, and means, controlled solely by the angular position of said arm about said pivot, automatically conditioning said switch to connect said unit with said recording circuit when said arm is in said recording position, and to connect said unit with said reproducing circuit when said arm is in said reproducing position.

5. In a disc sound recording and reproducing

machine, a rotatable record turntable, a disc record carried by said turntable and rotatable therewith, a support manually movable in a plane substantially parallel to that of said record to a reproducing position over one portion of said record and to a recording position over a different portion of said record, a recording-reproducing unit pivotally mounted on said support and capable of vertical movement about a horizontal pivot axis, a stylus carried by said unit and adapted to operatively contact the face of said record in either of said positions, and means acting upon said support when in said reproducing position to cause said horizontal pivot axis to assume a predetermined vertically spaced relation with the face of said record, and a substantially different vertically spaced relation therewith when said support is in said recording position.

6. In a disc sound recording and reproducing machine, a rotatable record turntable, a disc record carried by said turntable and rotatable therewith in a substantially horizontal plane, an arm pivot located outside of the periphery of said record, an arm manually movable about said pivot in a substantially horizontal plane to a recording position located to one side of a vertical plane passing through both said pivot and the axis of rotation of said record, and to a reproducing position located on the opposite side of said vertical plane from said recording position, a recording-reproducing unit pivotally mounted on said arm and capable of vertical movement about a horizontal pivot axis, a stylus carried by said unit and adapted to operatively contact the face of said record in either of said positions, and means supporting said arm when in said recording position to cause said horizontal pivot axis to assume a predetermined vertically spaced relation with the face of said record, and a substantially different vertically spaced relation therewith when said arm is in said reproducing position, whereby said stylus assumes a different vertical angle with the face of said record for each of said positions.

7. In a disc sound recording and reproducing machine, a record turntable rotatable about a record spindle, a disc record carried by said turntable and rotatable therewith, a recording-reproducing unit, a support carrying said unit and manually movable, in a plane substantially parallel to that of said record, to a reproducing position above said record and to one side of said spindle, and to a recording position above said record and to the opposite side of said spindle, a recording stylus-tip and a reproducing stylus-tip carried by said unit and adapted to alternately contact the face of said record, and means, controlled solely by the manual movement of said support to opposite sides of said spindle, causing the surface of said record to be operatively contacted by the said recording stylus tip when said support is in said recording position and by the said reproducing stylus tip when said support is in said reproducing position.

8. In a sound recording and reproducing machine, a rotatable record turntable, a disc record carried by said turntable and rotatable therewith in a substantially horizontal plane, an arm pivot located outside of the periphery of said record, a recording-reproducing unit, an arm carrying said unit and manually rotatable, in a substantially horizontal plane about said pivot, to a reproducing position located to one side of a plane passing vertically through both said pivot and the axis of rotation of said record, and to a

recording position located on the opposite side of said vertical plane from said reproducing position, a reproducing stylus-tip and a recording stylus-tip carried by said unit and adapted to alternately contact the face of said record, and means controlled solely by the horizontal angular position of said arm about said arm pivot, to cause said reproducing stylus-tip to operatively contact the face of said record when said arm is in said reproducing position, and to cause said recording stylus-tip to operatively contact the face of said record when said arm is in said recording position.

9. In a sound recording and reproducing machine, a rotatable record turntable, a disc record carried by said turntable and rotatable therewith in a substantially horizontal plane, a stylus having a recording face and an oppositely disposed reproducing face, a recording-reproducing unit carrying said stylus, and a support carrying said unit and movable, in a substantially horizontal plane, to a recording position located entirely to one side of a vertical plane passing through the axis of rotation of said record, and to a reproducing position located entirely to the opposite side of said vertical plane from said recording position, said support by its movement causing the recording face of said stylus to operatively engage the advancing face of said record during rotation thereof when said support is in said recording position, and further causing the oppositely disposed reproducing face of said stylus to operatively engage the advancing face of said record when said support is in said reproducing position.

10. In a disc sound recording and reproducing apparatus, a rotatable record turntable, a disc record carried by said turntable and rotatable therewith, an arm pivot located outside of the periphery of said turntable, an electro-mechanical recording-reproducing unit, an elongated arm carrying said unit and manually rotatable about said pivot, in a plane substantially parallel to and above said record, to a reproducing position on one side of a plane passing through both the axes of rotation of said arm and said record, and to a recording position on the opposite side of said last-mentioned plane, a reproducing circuit, a recording circuit, a circuit switch controlling the electrical connections of said unit with said reproducing and recording circuits, and a trip member carried by said arm and adapted to automatically engage a complementary member carried by said switch as said arm is moved across said record, whereby said unit is connected with said reproducing circuit when said arm is in said reproducing position, and with said recording circuit when said arm is in said recording position.

11. In an electric sound recording and reproducing apparatus, the combination with a reversible recording-reproducing unit and a multiple position circuit control switch having a rotatable control shaft adapted to change the external electrical connections of said unit, of a tone-arm carrying said unit and rotatable about an axis spaced from and substantially parallel to that of said control shaft, a plurality of angularly spaced trip members carried by said tone-arm and extending radially from the axis of rotation thereof, and a plurality of angularly spaced complementary members carried by said control shaft and extending radially therefrom and adapted to engage intermittently with said trip members in meshing relation therewith as said tone-arm is

rotated about its axis, whereby the rotation of said tone-arm results in an intermittent rotation of said switch control shaft in predetermined relation therewith.

12. In an electric sound recording and reproducing apparatus, the combination with a recording-reproducing unit and a circuit control switch adapted to change the external electrical connections of said unit, of a manually rotatable arm carrying said unit and pivoted for angular motion in a horizontal plane and limited angular motion in a vertical plane, a set of horizontally spaced trip members carried by said arm, and a corresponding set of complementary horizontally spaced members carried by the control member of said switch and adapted to engage intermittently with said trip members in meshing relation therewith as said arm is manually rotated, at least one of said sets of members being extended in a vertical plane, whereby the horizontal rotation of said arm causes an intermittent movement of the control member of said switch in predetermined relation therewith, regardless of the vertical angular position of said arm within its limits of vertical movement.

13. In a disc sound recording and reproducing apparatus, a rotatable record turntable, a disc record carried by said turntable and rotatable therewith, an arm pivot located outside of the periphery of said turntable, an electro-mechanical recording-reproducing unit, an arm carrying said unit and rotatable about said pivot, in a plane substantially parallel to and above said record, to a reproducing position located to one side of a plane passing through both the axes of rotation of said arm and of said record, and to a recording position located to the opposite side of said last-mentioned plane, a reproducing circuit, a recording circuit, a multiple position switch controlling the electrical connections of said unit with said reproducing and recording circuits and having a rotatable control shaft with its axis of rotation spaced from and substantially parallel to said arm pivot, a plurality of angularly spaced trip members carried by said arm and extending radially from the axis of rotation thereof, and a plurality of angularly spaced complementary members carried by said control shaft and extending radially therefrom and adapted to mesh intermittently with said trip members as said arm is rotated about its axis, whereby said switch is automatically controlled to connect said unit with said reproducing circuit when said arm is in said reproducing position, and with said recording circuit when said arm is in said recording position.

14. In a disc sound recording and reproducing machine, a rotatable record turntable, a disc record carried by said turntable and rotatable therewith, an arm pivot located outside of the periphery of said turntable, an arm manually rotatable about said pivot, in a plane substantially parallel to and above that of said record, to a reproducing position located to one side of a line passing through both the axes of rotation of said arm and said record, and to a recording position located to the opposite side of said line from said reproducing position, a recording-reproducing unit carried by said arm, a feed-bar rotatable about a pivot in a plane substantially parallel to and below that of said record, a feed mechanism operatively connected to said feed-bar and adapted to cause slow rotation thereof about its pivot, and means operatively coupling

said arm with said feed-bar when said arm is in said recording position only.

15. In a disc sound recording and reproducing machine, a rotatable record turntable, a disc record carried by said turntable and rotatable therewith, a recording-reproducing unit, an arm pivot located outside of the periphery of said turntable, an arm carrying said unit and manually rotatable, in a plane substantially parallel to and above that of said record, to a reproducing position located to one side of a vertical plane passing through both the axes of rotation of said arm and said record, and to a recording position located to the opposite side of said vertical plane from said reproducing position, a feed-bar coaxially pivoted with said arm but normally detached therefrom and movable in a plane below said record, a feed mechanism operatively connected with said feed-bar and adapted to cause slow rotation thereof about its pivot, and releasable complementary coupling means carried by said arm and said feed-bar causing operative feeding engagement of said feed-bar with said arm when the latter is in said recording position, and releasing said feed-bar from operative engagement with said arm when the latter is in said reproducing position.

16. In a disc sound recording and reproducing machine, a rotatable record turntable, a disc record carried by said turntable and rotatable therewith in a substantially horizontal plane, a recording-reproducing unit, an arm carrying said unit and rotatable about a pivot located outside of the periphery of said turntable, in a substantially horizontal plane, to a reproducing position located to one side of a vertical plane passing through both the axes of rotation of said arm and said record, and to a recording position located on the opposite side of said vertical plane, and means acting to displace at least a portion of said arm vertically with respect to said record surface as said arm passes from one of said positions to the other, whereby said arm is supported in a predetermined vertically spaced relation with said record surface, when in said recording position, substantially different from that in said reproducing position.

17. In a disc sound recording and reproducing machine, a rotatable record turntable, a disc record carried by said turntable and rotatable therewith, an arm pivot located outside of the periphery of said turntable, an arm rotatable

about said pivot, in a plane substantially parallel to and above that of said record, to a recording position located to one side of a vertical plane passing through both the axes of rotation of said arm and said record, and to a reproducing position located on the opposite side of said vertical plane, a recording-reproducing unit carried by said arm, a stylus carried by said unit and adapted to operatively engage the surface of said record in either of said positions, a stylus feed mechanism, means releasably coupling said arm with said feed mechanism when said arm is in said recording position, and further means acting upon said arm to cause the axis of said stylus to assume a predetermined angular relation with the surface of said record when said arm is in said recording position, and to assume a substantially different angular relation with the surface of said record when said arm is in said reproducing position.

18. In a disc sound recording and reproducing machine, a rotatable record turntable, a disc record carried by said turntable and rotatable therewith in a substantially horizontal plane, an arm pivot located outside of the periphery of said turntable, an arm rotatable about said pivot, in a plane substantially parallel to and above that of said record, to a reproducing position located to one side of a vertical plane passing through both the axes of rotation of said arm and said record, and to a recording position located on the opposite side of said vertical plane from said reproducing position, a feed-bar coaxially pivoted with said arm and movable in a plane substantially parallel to and below that of said record, a feed-mechanism operatively connected with said feed-bar and adapted to impart a slow motion thereto about its pivot, a recording-reproducing unit movable about a substantially horizontal pivot carried by said arm, a stylus carried by said unit and adapted to operatively engage the surface of said record, means supporting said arm in a vertically spaced relation with the surface of said record when said arm is in said reproducing position and out of operative connection with said feed-bar, and means rendering said first-mentioned means inoperative when said arm is brought into said recording position and permitting said arm to be lowered into operative engagement with said feed-bar.

JACOB H. REBOLD.
